(57) CLAIM

The ornamental design for a computer desk as shown and described.

DESCRIPTION

FIG. 1 is a perspective view of a computer desk showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a rear, bottom side perspective view thereof;
FIG. 9 is an enlarged detail view of area 9 shown in FIG. 7;
FIG. 10 is an enlarged detail view of area 10 shown in FIG. 7;
FIG. 11 is an enlarged detail view of area 11 shown in FIG. 8; and
FIG. 12 is an enlarged detail view of area 12 shown in FIG. 8.
FIG. 13 is an enlarged detail view of area 13 shown in FIG. 2.
FIG. 14 is an enlarged detail view of area 14 shown in FIG. 2.
FIG. 15 is an enlarged detail view of area 15 shown in FIG. 2.
FIG. 16 is an enlarged detail view of area 16 shown in FIG. 2.
FIG. 17 is an enlarged detail view of area 17 shown in FIG. 2.
FIG. 18 is an enlarged detail view of area 18 shown in FIG. 2.
FIG. 19 is an enlarged detail view of area 19 shown in FIG. 4.
FIG. 20 is an enlarged detail view of area 20 shown in FIG. 4.
FIG. 21 is an enlarged detail view of area 21 shown in FIG. 5.
FIG. 22 is an enlarged detail view of area 22 shown in FIG. 5.
FIG. 23 is an enlarged detail view of area 23 shown in FIG. 7.
FIG. 24 is an enlarged detail view of area 24 shown in FIG. 7; and,
FIG. 25 is an enlarged detail view of area 25 shown in FIG. 7.

The broken lines in the drawings depict portions of the computer desk that form no part of the claimed design.
